UNITED STATES PATENT OFFICE

161,346

BED COMFORTER

Max Katz, Fort Worth, Tex.

Application February 20, 1950, Serial No. 8,026

Term of patent 14 years

(Cl. D92—2)

To all whom it may concern:

Be it known that I, Max Katz, a citizen of the United States, residing at Fort Worth, in the county of Tarrant and State of Texas, have invented a new, original, and ornamental Design for Bed Comforter, of which the following is a specification, reference being had to the accompanying drawing, forming part thereof.

The figure is a plan view of a bed comforter, showing my new design.

I claim:

The ornamental design for a bed comforter, substantially as shown.

MAX KATZ.
